UNITED STATES PATENT OFFICE.

ALBERT G. DAVIS, OF SCHENECTADY, NEW YORK, ASSIGNOR TO GENERAL ELECTRIC COMPANY, A CORPORATION OF NEW YORK.

INCANDESCENT LAMP.

1,082,012.

Specification of Letters Patent. Patented Dec. 23, 1913.

Application filed September 23, 1907. Serial No. 385,024.

To all whom it may concern:

Be it known that I, ALBERT G. DAVIS, a citizen of the United States, residing at Schenectady, county of Schenectady, State of New York, have invented certain new and useful Improvements in Incandescent Lamps, of which the following is a specification.

My present invention relates to incandescent electric lamps and more particularly to lamps having filaments of a refractory metal.

Incandescent lamp filaments of tantalum, tungsten, osmium, and similar refractory elements, are operative at exceedingly high temperatures, and consequently at relatively high efficiencies. Owing to their high operating temperature, and to their small cross-section and somewhat fragile nature, considerable care must be exercised in designing the lamp in which these filaments are to run. The difficulties are different from those experienced with carbon lamps. Details of construction which have been regarded as standard for carbon lamp manufacture must in many instances be entirely discarded.

Lamp filaments of the refractory elements above mentioned have a tendency to become deformed while running at very high temperatures and must ordinarily be anchored or otherwise held in fixed position with respect to the lamp bulb. It has heretofore been customary to anchor filament loops by wires or hooks of refractory material, such as thorium oxid. Owing to the high running temperature of the filament, difficulty has been experienced in preventing fusion of the filament to the anchoring device and in preventing chemical disintegration of the anchoring device induced by the close proximity of the highly heated metal of the filament.

According to my present invention, certain portions of the refractory metal filament are reinforced or made larger, with the result that the reinforced portions radiate more heat than other portions and therefore remains at a lower temperature. By reinforcing the filament at the point of support or anchorage, the difficulty of fusion with the anchor, or of chemical dis-

integration of the anchoring material, is entirely obviated. The local reinforcements offer other advantages as hereinafter pointed out more in detail.

The novel features of my invention are particularly pointed out in the appended claim, for a better understanding of which, reference may be had to the following description taken in connection with the accompanying drawings.

Figure 1 is a perspective view of an incandescent lamp embodying my invention; Fig. 2 is an enlarged detail of a filament reinforced at the point of anchorage; Fig. 3 is an enlarged detail showing reinforcement at the point of current supply; and Fig. 4 illustrates a modification in which the reinforcement is at the extreme end of the filament loop.

Tungsten and some of the other refractory elements above mentioned are ordinarily obtainable in the form of a non-coherent powder which cannot be shaped into filaments or conductors without the use of some special process. In order that my invention may be readily practised, I have hereinafter described a method quite suitable for the manufacture and reinforcement of lamp filaments of any of the materials above mentioned, as well as of mixtures or alloys thereof with other materials; in fact, a method applicable to any refractory metal or material of that general class of which tungsten is typical.

The process above mentioned will be described with particular reference to tungsten.

To secure the reinforcement contemplated by my present invention, I prefer to make use of small tubes, preferably of the same material as the filament, slipped into place on the filament after the latter has been completely shrunk and sintered. Tubes suitable for this purpose may be made by a method quite analogous to that used for the filament manufacture. Tungsten powder obtained by reduction of tungsten trioxid with hydrogen according to known chemical processes may be employed for the production of these tubes. If desired, finely divided tungsten trioxid which has been purified and then ground and sorted may be used. In order to shape the finely divided

tungsten into the tube, I may mix the powder with binding material, extrude or roll the mixture into flat ribbons, draw these ribbons through a relatively large die to curl them up into long tubes having a bore comparable to the diameter of a lamp filament, and finally treat these tubes to remove the components of the binder and to sinter and shrink the refractory residue to render it strong and solid. I prefer to use a binder consisting of a ductile alloy composed of metals which can be easily vaporized out of the mixture in order that the resulting liquid may be entirely free from carbon. Such a ductile alloy may be made by melting together 42 parts cadmium and 58 parts mercury and then adding five parts bismuth. This alloy can be mixed or impregnated with tungsten by merely rubbing the two together while the alloy is in a warm and plastic state. The binder does not appear to chemically combine with the tungsten with which it is impregnated, but seems to form a mechanical mixture by which the particles of tungsten are held together by the ductile alloy. The applicability of this process to materials other than tungsten is readily apparent. Various proportions of tungsten and binder may be used, but a mixture containing tungsten to the extent of 30 to 40 per cent. by weight of the final mixture gives good results. Such a mixture is ductile and pliable and can be readily rolled or worked by any of the metal working processes. A squinting temperature of 120 to 150 degrees centigrade is satisfactory. The tubes are then baked to drive out the mercury and some of the cadmium, as by placing them grouped in bundles on a piece of wire gauze supported in an evacuated glass tube and heating the tube with a Bunsen burner. Most of the bismuth and some of the cadmium stay behind with the tungsten in this baking operation. The tubes are next suspended in treating bottles (as, for example, between metallic clamps) and heated with current to drive out the remainder of the binder. The treating bottle should be evacuated with a good mechanical pump and should be maintained dry by the use of an absorbing agent, such as phosphorous pentoxid, preferably placed in close proximity to the tube, as in a small dish immediately beneath it. The treatment may be effected by passing a low current through the tube for, say, 10 or 15 seconds, and then a higher current for 15 to 30 seconds, or even for a minute. The low current heats it sufficiently to drive out the remaining cadmium and bismuth; and the high current sinters the residue and shrinks it in a compact homogeneous body having a bright metallic surface. When finished, therefore, the tubes consist entirely of sintered tung-

sten. They may then be cut or broken in short lengths and slipped on over the tungsten filaments to serve as local reinforcements. To secure the best coöperation between the reinforcing tube and filament, there should be an intimate contact between the two. I find, however, that this close union between the parts is easily obtainable, it being only necessary to slip the tube in place and then pass normal current through the filament, whereupon the filament by virtue of its high temperature sinters or sticks to the tube along one side or at several points. The resultant product is about the same as if the reinforcing tube were an integral part of the inclosed filament.

Filaments locally reinforced as above described may be mounted as shown in Fig. 1 of the drawing. This figure shows a lamp provided with four filament loops 1, 2, 3 and 4 provided with reinforcements 5 for engagement with the anchoring hooks 6. As previously indicated, these reinforcements serve to cool the filament at the point of anchorage and by so doing prevent decomposition of the anchors and fusion with the filament.

In addition to the local reinforcements above mentioned, I may use similar reinforcements 7 at the ends of each filament loop where connection is made with the current supply wires 8. This feature is illustrated on an enlarged scale by Fig. 3 of the drawings. Reinforcements at the ends of the filament legs serve not only to locally cool the filament but also serve to protect the filament from contamination by the material of the current supply wire. If the latter be welded to the filament as shown in Fig. 3, the local enlargement has the further function of protecting the filament from overheating or oxidation during the welding operation. This protection is secured even though the welds be made with great rapidity and by careless workmen.

Fig. 4 shows a somewhat different application of my invention in that the reinforcement 9 is at the extreme end of the filament loop where it engages with an anchoring or supporting hook 10. A reinforcement of this sort serves not only to locally cool the filament, but also serves to separate the two legs of the filament and prevent accidental short-circuit in case of slight deformation of the filament legs.

In order to construct a curved local reinforcement as shown in Fig. 4, the process of assembling must be somewhat different from that above described. In general, I prefer to make straight tubes and to have the filament in a straight or partially looped condition, and then slip the tube over the filament to its proper position and subsequently curve the whole into the form shown

in Fig. 4 by wrapping the members around a mandrel heated to a temperature somewhat less than red heat.

What I claim as new, and desire to secure 5 by Letters Patent of the United States, is,—

The combination with a refractory metal filament loop having its bend reinforced

with refractory metal of an anchoring device loosely engaging said reinforced bend. 10

In witness whereof, I have hereunto set my hand this 25th day of September, 1907.

ALBERT G. DAVIS.
